Primary Examiner — Philip S Hyder*(74) Attorney, Agent, or Firm* — Tarolli, Sundheim, Covell & Tummino LLP; John A. Yirga, Esq.(57) **CLAIM**

The ornamental design for a dehiding tool, as shown and described.

DESCRIPTION

FIG. 1 is an upper-right perspective view illustrating my ornamental design comprising a dehiding tool;

FIG. 2 is an upper-left perspective view thereof;

FIG. 3 is a lower-right perspective view thereof;

FIG. 4 is a lower-left perspective view thereof;

FIG. 5 is a bottom-plan view thereof;

FIG. 6 is a top-plan view thereof;

FIG. 7 is a left-side elevation view thereof;

FIG. 8 is a right-side elevation view thereof;

FIG. 9 is a front-elevation view thereof;

FIG. 10 is a rear-elevation view thereof;

FIG. 11 is a section view of FIG. 6 along section lines 11-11; and,

FIG. 12 is a section view of FIG. 9 along section lines 12-12. The broken lines depict portions of the dehiding tool in which the design is embodied that are not considered part of the claimed design.
